ROBOT CONTROLLED LIMB

Irving A. Goldman, Alexandria, Va.

Application May 15, 1948, Serial No. 27,272

7 Claims. (Cl. 3—12)

1

This invention relates to artificial limbs and in particular to one of the robot controlled type.

An important object of the invention is to provide means for controlling the movement of the fingers of a hand so that the finger joints thereof can be operated at the will of the wearer of the artificial arm so that the hand may be used to move things about and may be used to pick up articles and grip the same for use, such as a lead pencil, a book or the like.

Another important object of my invention is the provision of means in connection with a hand whereby the wearer can determine whether the article picked up or touched is hot or cold and if so, to what degree.

Another important object of the invention is to provide means whereby the operation of the fingers may be controlled as gripping members from a switch carried in the mouth of the wearer of the artificial limb so that a difference in biting pressure may be used to control the different outer and inner joints of the hand, a source of power being also included in the nature of a storage battery or power pack which may be carried around by the individual and which may be charged by him when he is at home.

Still further objects of my invention include the use of detecting means incorporated in the foot and leg structure of an artificial leg in which the unevenness of a surface walked upon may be sensed by the individual in the stump of the leg to which is secured the artificial limb; to provide in such a leg, a mechanical means which will indicate to the wearer for instance, the edge of a step or curbstone so that he will be aware of a step or unevenness of the ground; and to provide a switch mechanism for the control of the various parts.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure—

Fig. 1 is a view in perspective showing a person equipped with an artificial arm and using the invention as applied to the hand thereof for holding an implement.

Fig. 2 is a plan view of a hand and the mechanism for operating the parts thereof, together with the electrical circuit involved, the same being shown in diagrammatic arrangement.

Fig. 3 is an enlarged side view of the hand portion of the artificial limb, a part thereof being shown in section to illustrate the operating mechanism.

2

Fig. 4 is a view in section through a switch which is part of a control unit, a power pack being also shown.

Fig. 5 is a side view of a hand in which is incorporated temperature detecting means.

Fig. 6 is an enlarged fragmentary section taken through one of the fingers of the hand illustrated in Fig. 5 showing the contact member used against the surface of an object.

Fig. 7 is a view of the lower part of a body supported by an artificial leg in which has been incorporated detecting means.

Fig. 8 is an enlarged view taken on the line 8—8 of Fig. 7 illustrating the relative position of the parts of the detecting mechanism.

Fig. 9 is an enlarged view, partly in section of the foot portion of the artificial limb having the ground engaging detecting means shown in connection therewith.

Fig. 10 is an enlarged view in cross section, through the upper portion of the limb, showing the means employed for imparting to the stump supported in the artificial leg, indication of an uneven surface upon which the foot rests.

Fig. 11 is a diagrammatic view of a modified form of the sensing mechanism that may be employed in connection with the limb shown in Fig. 8.

Referring to the drawing in detail, the numeral 10 indicates the stump of an arm to which is attached, in the well known manner, an artificial arm 11 terminating in a hand 12. The hand, as illustrated in Fig. 3, while of the usual construction found in artificial hands, may, in this particular instance, be articulated as at 13 in the finger portions 14 thereof to provide for the pivotal movement of the outer, inner and intermediate joints 15, 16 and 17, respectively. The finger portions 14 are of hollow construction and in their pintle portions 13 may present square shafts 18 upon which are fixed the lever arms 19 in any suitable manner. The free ends of the arms are pivoted as at 20 to the cores 21 of solenoids 22 which operate against the tension of springs 23 to actuate the finger joints and position them as shown in outline in Fig. 3, so that any article may be gripped thereby and picked up.

For the purpose of illustration, I have employed only two sets of solenoids for the operation of the outer and intermediate finger joints; but it is to be understood that other sets may be used to operate not only the inner joints of the fingers but the wrist and elbow joints if so desired. Referring to Fig. 2, the solenoids 22 are arranged in rows and the upper row is connected through the medium of the wires 25 with a source of current 26 which in this instance may be a storage battery or a power pack 27 which may

be slung over the shoulder of the user of the artificial arm through the medium of the strap 28. Wires 29 connect an outer set of the solenoids 22 with the source of current and there is interposed in the lines 25 and 29 a control unit 30 (Fig. 4).

The control unit consists of a very minute housing 31 of cylindrical form in the opposite walls of which are imbedded the contacts 32 and 33, the housing being closed by a ring member 34 which imprisons a self-seating cylindrical contact switch 35 which is maintained against the ring 34 and in the upper part of the housing by a compression spring 36. This switch unit 30 is placed in the mouth of the person using the same when the fingers are to be operated, and positioned between the teeth so that the switch 35 can be depressed to bridge the contacts 32 first and then the contacts 33 to close the circuit through the line 29 first and, when the member 35 moves farther into the housing, through the line 25. The shape of the device 25 is such that after the circuit through the line 29 is closed and the switch 35 is fully depressed it will maintain the circuit already made and will complete a new circuit through the line 25. This action is necessary so that the fingers may be closed to pick up something, that is, the outer joints will be operated first and then the inner joints.

The wires 25 and 29 may be molded in the housing 31, as are the contacts, the wires being lead therefrom in a single cable casing 38, that is, connected to the power pack 27 in any suitable manner and from which said casing extends as at 37 to the artificial arm structure.

In Figs. 5 and 6, I have illustrated a temperature sensitive device that may be incorporated in the artificial hand structure either as a separate feature or in combination with the finger operating mechanism. This sensitive device consists of inserts or pads 40 molded or otherwise formed in the inner surface of the finger joints and in which is molded a large number of metallic pins 41 such as aluminum. These pins protrude very slightly beyond the surface of the pad 40 so that they may engage a surface touched by the hand and serve as heat or cold conductors. The pins 41 are connected through the medium of wires 42 extending from each finger pad 40 to a bimetal expansion and contact strip unit 43. The operation of a bimetal strip of this nature is well understood, it being sufficient to note that the degree of heat affecting it will cause it to bow and operate the pointer 44 to indicate, on the meter dial 45, opposite ranges of heat from a normal dial indication 46.

Referring to the form of the invention shown in Figs. 7 to 11, the stump of a leg 50 is shown mounted in the upper portion 51 of an artificial limb structure 52 comprising a leg portion 54 and a foot 55, articulated and controlled by any means common in artificial leg structures.

The purpose of the device is to give to the bottom surface of the stump a sensation in accordance with the roughness of the surface upon which the foot is resting so that it will be possible for instance, for the wearer to feel the edge of a curbing or other obstruction and to this end I provide a large number of Bowden wires 56 which consist of the usual casings 57 and inner wire 58. The bottom wall of the foot 55 is recessed as at 60 to provide a pocket in which the heads 61 of the wires 58 may rest, the ends of the casings 57 being suitably connected

5 in a holding plate 62 secured in any suitable manner to the bottom 63 of the foot 55.

When the foot is resting upon a flat surface, all of the heads 61 of the Bowden wires will be flush with the flanged edge 59 that extends about the bottom of the foot portion 55, but when the foot rests upon an uneven surface (Fig. 9), the latter, indicated as at 64, will depress the wires 58 and will lift them at their opposite ends as at 65. Said opposite ends are disposed at a point in the leg structure immediately beneath the supporting sock 66 in which the stump 50 is supported in the leg part 51. The ends of the wires 58 pass through a plate 67, are provided 15 with heads 68 and are arranged to engage plates or strips 69 over which is stretched a rubber sheet 70 which is secured at its ends to the member 67, which in turn is mounted on a suitable bracket 71 for support within the leg portion 51 and constitutes a holding means 72 into 20 which the upper ends of the wire casings 57 are secured.

The sheet 70 will be stretched taut across the plates 69 and will yieldably hold the heads 68 25 in their depressed position. When the foot rests on an uneven surface, the Bowden wires are pressed inwardly against the yielding action of the rubber sheet with the result that a section of the rubber sheet corresponding to a section 30 of the foot portion that engages the uneven surface is raised up and is pushed against the bottom of the leg stump and thus the individual will get the impression that the foot has stepped on something. As illustrated in Fig. 11, the 35 Bowden wire structure 75 may be separated and may have interposed between the ends thereof an adjustable link 76, through the medium of which the pushing action of the lower Bowden wire may be varied.

40 It is evident therefore, that I have provided an artificial limb structure which may be used to pick up articles, may be used to sense heat and cold and may be used to sense even and uneven surfaces.

45 While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

55 1. In an artificial hand having a plurality of tubular fingers, contact pads on the inner surfaces of each of the fingers, contact pins in the pads for engaging a surface to be felt, wires leading from said pins, a bimetal member to which the wires are joined to be influenced by differences 60 in temperature transferred from said contacts through said wires, and an indicator actuated by said bimetal member.

65 2. In an artificial hand having a plurality of tubular fingers, contact pads on the inner surfaces of each of the fingers, contact pins in the pads for engaging a surface to be felt, wires leading from said pins, a bimetal member to which the wires are joined to be influenced by differences 70 in temperature transferred from said contacts through said wires, and an indicator actuated by said bimetal member, said pads being flexible to conform closely to the contour of the surface engaged.

75 3. In an artificial hand having a finger formed

of a plurality of hollow end aligned finger portions with adjacent ends of the finger portions being slightly overlapped, pivot pins extended through the overlapped ends of the finger portions, each of said pivot pins being secured to one of the finger portions through which it is engaged and being rotatively extended through the other of the finger portions, a solenoid having a core for each of said pivot pins fixedly mounted in the finger portion through which the respective pivot pin is rotatively extended, levers each fixedly connected at one end to one of said pivot pins and at the other end to the core of the respective solenoid for turning the respective pivot pin to move the finger member when the solenoid is energized, spring means operating between each of said cores and a fixed part of the respective finger members for urging said cores into extended positions, and electrically operated circuit means connected to said solenoids and controlled by a manually operable switch for energizing said solenoids when said switch is closed.

4. In an artificial hand having a finger formed of a plurality of hollow end aligned finger portions with adjacent ends of the finger portions being slightly overlapped, pivot pins extended through the overlapped ends of the finger portions, each of said pivot pins being secured to one of the finger portions through which it is engaged and being rotatively extended through the other of the finger portions, a solenoid having a core for each of said pivot pins fixedly mounted in the finger portion through which the respective pivot pin is rotatively extended, levers each fixedly connected at one end to one of said pivot pins and at the other end to the core of the respective solenoid for turning the respective pivot pin to move the finger member when the solenoid is energized, spring means operating between each of said cores and a fixed part of the respective finger member for urging said cores into extended positions, and electrically operated circuit means connected to said solenoids and controlled by a manually operable switch for energizing said solenoids when said switch is closed, said switch means being operable to energize said solenoids one after the other.

5. In artificial hand having a finger formed of a plurality of hollow end aligned finger portions with adjacent ends of the finger portions being slightly overlapped, pivot pins extended through the overlapped ends of the finger portions, each of said pivot pins being secured to one of the finger portions through which it is engaged and being rotatively extended through the other of the finger portions, a solenoid having a core for each of said pivot pins fixedly mounted in the finger portion through which the respective pivot pin is rotatively extended, levers each fixedly connected at one end to one of said pivot pins and at the other end to the core of the respective solenoid for turning the respective pivot pin to move the finger member when the solenoid is energized, spring means operating between each of said cores and a fixed part of the respective finger member for urging said cores into extended positions, and electrically operated circuit means connected to said solenoids and controlled by a manually operable switch for energizing said solenoids when said switch is closed, said switch comprising a hollow housing of insulation material, sets of contacts connected in series in said circuit mounted in diametrically opposite sides of the inner wall of said housing, a movable switch

member slidably extended from said housing to be pushed inward for bridging said sets of contacts, and means retaining said switch member yieldably in an inoperative position extended from said housing.

6. In artificial hand having a finger formed of a plurality of hollow end aligned finger portions with adjacent ends of the finger portions being slightly overlapped, pivot pins extended through the overlapped ends of the finger portions, each of said pivot pins being secured to one of the finger portions through which it is engaged and being rotatively extended through the other of the finger portions, a solenoid having a core for each of said pivot pins fixedly mounted in the finger portion through which the respective pivot pin is rotatively extended, levers each fixedly connected at one end to one of said pivot pins and at the other end to the core of the respective solenoid for turning the respective pivot pin to move the finger member when the solenoid is energized, spring means operating between each of said cores and a fixed part of the respective finger member for urging said cores into extended positions, and electrically operated circuit means connected to said solenoids and controlled by a manually operable switch for energizing said solenoids when said switch is closed, said switch being of a size to be positioned between the teeth of the wearer of the hand to be operated by opening and closing of the jaws.

7. In artificial hand having a finger formed of a plurality of hollow end aligned finger portions with adjacent ends of the finger portions being slightly overlapped, pivot pins extended through the overlapped ends of the finger portions, each of said pivot pins being secured to one of the finger portions through which it is engaged and being rotatively extended through the other of the finger portions, a solenoid having a core for each of said pivot pins fixedly mounted in the finger portion through which the respective pivot pin is rotatively extended, levers each fixedly connected at one end to one of said pivot pins and at the other end to the core of the respective solenoid for turning the respective pivot pin to move the finger member when the solenoid is energized, spring means operating between each of said cores and a fixed part of the respective finger member for urging said cores into extended positions, and electrically operated circuit means connected to said solenoids and controlled by a manually operable switch for energizing said solenoids when said switch is closed, said switch being usable at a point on the body of the wearer of the hand remote from the hand, and cables connecting said switch with said solenoids and a source of power for said circuit.

IRVING A. GOLDMAN.
